James McCann

INVENTOR.

BY

Richard Blum,

ATTORNEY.

UNITED STATES PATENT OFFICE.

JAMES McCANN, OF GAGE, MONTANA.

HEATING-STOVE.

1,368,405.

Specification of Letters Patent. Patented Feb. 15, 1921.

Application filed February 11, 1919. Serial No. 276,362.

To all whom it may concern:

Be it known that I, JAMES McCANN, a citizen of the United States, residing at Gage, in the county of Musselshell and State 5 of Montana, have invented certain new and useful Improvements in Heating-Stoves, of which the following is a specification.

This invention relates to heating stoves, and more particularly to what are known 10 as base heater stoves.

The object of the invention is to construct a heater of this character with means for utilizing heat which has been heretofore wasted.

15 Another object is to construct a heater of this character with an additional chamber arranged between the ash pan containing chamber and the heat and smoke flues to provide for the utilization of the heat from 20 said flues which was heretofore absorbed or smothered by the ash pan, and which is equipped with deflectors for throwing the heated air out of the chamber into the surrounding atmosphere.

25 With the foregoing and other objects in view, which will appear as the description proceeds, the invention resides in the combination and arrangement of parts and in the details of construction hereinafter described 30 and claimed, it being understood that changes in the precise embodiment of the invention herein disclosed may be made within the scope of what is claimed without departing 35 from the spirit of the invention.

35 In the accompanying drawings:—

Figure 1 represents a vertical section of a stove equipped with this invention; and

Fig. 2 is a similar view taken in a plane at right angles to Fig. 1.

40 In the embodiment illustrated, a base heater stove is shown, equipped with this improvement.

The usual flue chamber 1 is shown having an ash pan receiving chamber 2 disposed 45 above it and between which chamber is arranged an intermediate chamber 3 which may be termed, and is hereinafter called a heat liberating chamber. The ash pan chamber 2 has no communication with the 50 upstanding flue 4. Chamber 1 constitutes what is known as the flue chamber in stoves of this character and with which communicate the down draft flues 5 and 6 and the up draft flue 4.

55 The chamber 3 which constitutes the gist of this invention has side doors 8 hinged at

9 to open downwardly and each carrying on its inner face a rack bar 10 which is designed for interlocking engagement with a flange 11 inside the chamber 3 and as here shown 60 formed on the outer edge of a double deflector 12, the two members of which extend longitudinally of the chamber 3, being curved transversely so that the heated air impinging against their lower faces will be 65 directed outwardly through the openings in the side of the chamber when the doors 8 are open, it being obvious that the extent that the doors are opened may be controlled by the engagement of the rack bars 10 with 70 the flanges 11. This deflector 12 is shown composed of two members which are shown integral, being united at their lower edges whereby a deflector V-shaped in cross section is provided. A front door 13 is hinged at 75 14 at the front of chamber 3 to open upwardly and carries on its inner face a curved rack bar 15 designed to engage an upstanding lug 16 at the bottom of chamber 3 near its front as is shown clearly in Fig. 1. The rack bars 80 10 and 15 are all pivotally mounted and provided on the outside of the chamber with actuating handles 17 so that when it is desired to open the doors the bars are swung to disengage them from their coöperating 85 locking elements and the doors then open to the proper distance and the bars swing back into engagement with said elements. This arrangement of the doors provides for a draft in chamber 3 when all the doors are 90 open, the air entering through the door opening of door 13 and passing out through the door opening of doors 8.

The usual fire pot 18 with a grate 19 at its bottom is shown with an ash pan 20 arranged in chamber 2 below the fire pot to receive the ashes which sift through the grate.

In the use of this improved stove, the heat from the flue chamber 1 which is usually 100 absorbed by the ash pan disposed directly over it is radiated into chamber 3 and passed out through the side openings at the will of the owner according to the adjustment of the respective doors. The deflector 105 12 is removably mounted in the chamber 3 so that if desired it may be taken out for cleaning and other purposes through the front opening which is closed by the door 13.

The foregoing description and the drawings have reference to what may be considered the preferred or approved form of

my invention. It is to be understood that I may make such changes in construction and arrangement and combination of parts, materials, dimensions, etc., as may prove expedient and fall within the scope of the claimed invention.

Having thus fully described my invention, what I claim as new and desire to secure by Letters Patent, is:—

- 10 1. A base heater for stoves having a flue chamber and an ash pan containing chamber arranged thereover with a heat liberating chamber disposed between them, oppositely disposed doors for said heat liberating chamber, and a deflector arranged in said chamber for directing the heated air out through the door openings.
- 15 2. A base heater for stoves having a flue chamber and an ash pan containing chamber arranged thereover with a heat liberating chamber disposed between them, oppositely disposed doors for said heat liberating chamber, a deflector substantially V-shaped in cross section arranged in said chamber
- 20

with its apex resting on the bottom of the 25 chamber and operable to discharge the heated air through the door openings.

3. A base heater for stoves having a flue chamber and an ash pan containing chamber arranged thereover with a heat liberating 30 chamber disposed between them, oppositely disposed doors for said heat liberating chamber, a deflector substantially V-shaped in cross section arranged in said chamber with its apex resting on the bottom of the 35 chamber and operable to discharge the heated air through said doors, said deflectors having depending flanges on their outer edges, and a rack bar carried by each of said doors for co-operative engagement with one 40 of said flanges to hold the doors in adjusted position.

In testimony whereof I affix my signature in presence of two witnesses.

JAMES McCANN.
